SHINGLE

Norman P. Harshberger, Scarsdale, N. Y., assignor to Bakelite Building Products Co. Inc., New York, N. Y., a corporation of Delaware

Application September 29, 1931, Serial No. 565,882

19 Claims.

(Cl. 108—7)

This invention, relating, as indicated, to a shingle is more particularly directed to a shingle of the type known as a composition shingle. Generally, such shingles are cut from various materials which are of a flexible fibrous nature, but it is to be understood that the invention is not confined to such materials and that my improved shingle may be made from metal, hydraulic cement or the like. It is also to be understood that although I refer to the invention as relating to a shingle it may be equally adapted for use as siding.

The shingle contemplated by this invention is a shingle of the interlocking type, but one which is lacking entirely in slots or slits which render most shingles liable to tearing and other destruction. Heretofore, a number of interlocking shingles have been provided but in every instance the interlock takes place at a fixed point on the shingle and allows no variation in the amount of lap, or the point at which the shingle is secured, as by nailing. The shingles of the prior art are further objectionable in that where an interlocking shingle was provided it was necessary to turn up a corner and insert the interlocking projections in a slot, all of which consumed considerable time of the roofer.

It is a further object of the invention to provide an interlocking shingle which can be cut from a strip of sheet roofing without any waste.

The annexed drawing and the following description set forth in detail certain mechanism embodying the invention, such disclosed means constituting, however, but one of the various mechanical forms in which the principle of the invention may be used.

In said annexed drawing:—

Fig. 1 is a plan view taken from above of an individual shingle; Fig. 2 is a plan view of a strip 40 of sheet roofing showing the manner in which the shingle in Fig. 1 is cut therefrom; Fig. 3 is a plan view taken from above of a series of shingles in assembled position on a roof; Fig. 4 is a plan view of an individual shingle which is a modification of the shingle shown in Fig. 1; Fig. 5 is a view similar to Fig. 2 of the modification, and Fig. 6 is a plan view of a further modification.

Referring now to the drawing, and especially to Fig. 1, it will be seen that my improved shingle 10 consists of a polygonal body portion having longitudinal sides 11 and 12, which extend in substantially parallel relation. At one end of the shingle a plane edge 13 connects the edges 11 and 12, and at the opposite end an edge of irregular contour is formed consisting of a main

portion 14 having a tab 15 at one end thereof and a notch 16 at the other end. The tab 15 is formed by the outer edge portion 17, which is approximately parallel to the end 13, and the inwardly connecting portion 18 extending at an angle to the outer edge 17. At the other corner of the end 14 the notch 16 is defined by the edge 19 extending substantially parallel with the edge 13 and the edge 20 which extends substantially parallel with the edge 18.

As will be seen from an inspection of Fig. 2, the tab and notch define equal areas and are bounded by edges equal in length, thus providing a means of cutting the shingles from a strip of material without any waste whatsoever.

In Fig. 3 I have depicted the manner in which a slight modification of my improved shingle is most easily laid. In this figure the dotted line 25 represents an imaginary line drawn parallel to the ridge of the roof, and it will be seen that contrary to the usual procedure in the laying of the shingles only one corner touches this line. It will be further noted that the edges 11 and 12 extend at an acute angle to this line, and not as is customary parallel thereto. The end edges 13 and 14, on the contrary, extend in lines normal to the line 25, and the shingles, as shown, are laid from the left to the right, the first shingle 10 being held in place by the nail 24 and the second shingle 10' having its tab portion 15' inserted under the edge 12 of the shingle 10. It will readily be appreciated that the tab 15 may be inserted along the length of the edge 12, and also that the nail 24 may be driven in at any point corresponding to the interlock. In this manner the lap is securely held and the interlock itself instead of being at the weakest point of the shingle takes place at the most secure point.

In the modification shown in Fig. 4, the shingle is shown as having a main body portion 30, a plane end edge 31, and an opposite end edge 32 which has a tab 40 at one end, and a notch 43 at the opposite end. In this instance the longitudinal edge does not form an unbroken line but consists of an edge 33 and an edge 34 connected by a smaller edge 35. In like manner the lower edge connecting the ends consists of the edges 36 and 37 connected by the edge 38. The tab 40 is defined by the outer edge 41 which extends approximately parallel to the edges 31, 32 and 38, and is connected to the main body portion by the angularly directed edge 42. The notch 43 is defined by an edge 45 substantially parallel to the edges 31, 32 and 35 and connected to the outer edge 32 by the edge 44. This shingle can be cut

from a strip of roofing without any waste, as clearly shown in Fig. 5, and when laid, presents a different appearance from the shingle 10. The tab 48 is interlocked at any point along the edge 37 so that again a shingle is provided which can be variably interlocked along a plane edge. This shingle, however, is restricted in flexibility of amount of lap but ordinarily it is not desired to overlap more than one-half of the shingle.

10 A still further modification of the shingle shown in Fig. 1 is shown in Fig. 6, in which the shingle 50 has the general shape of a parallelogram with side edges 53 and 54 extending substantially parallel. The remaining edges 51 and 52 do not extend in parallel relation because of the form of the edge 52. This edge is directed upwardly into the shingle forming the offset 61 which is defined by the small edges 55, 56 and 57. It will, of course, be understood that the small edge 56 is approximately parallel to the upper edge 51. At an adjacent corner of the shingle a lug 58 is formed which is adapted to slidably and adjustably interlock with the edge 52. The slot 59 makes this possible. The edge 60 of the lug is approximately parallel to the small edge 55 so as to enable the shingle to be cut with less waste. This shingle is laid up reversely to the shingle shown in Fig. 3, the roofer starting from the right hand side of the roof 30 and working toward the left.

From the preceding description it will be seen that I have provided a shingle as shown in Figs. 1, 3 and 4 which has no slots but one which can be interlocked with an adjacent shingle. It will also be noted that the amount of lap can be varied and that the nailing of the shingle can be varied, thus providing a means of securing the shingle at the interlock. It will further be seen that the shingle can be interlocked with remarkable ease in sharp distinction to ordinary interlocking shingles where the roofer must carefully insert some sort of interlocking projection in a slot.

Another important advantage is that the shingles can be laid without regard for the joint of the lower course, and that the shingle illustrated in Figs. 1, 3 and 4 can be cut from a small width of sheet roofing without any waste whatever, except that which may occur at the beginning and 50 end of a strip.

Other modes of applying the principle of my invention may be employed instead of the one explained, change being made as regards the mechanism herein disclosed, provided the means 55 stated by any of the following claims or the equivalent of such stated means be employed.

I therefore particularly point out and distinctly claim as my invention:—

1. A shingle having side edges and end edges, 60 said end edges extending in a line approximately normal to the ridge of a roof upon which said shingle is so laid, and said side edges extending at acute angles to said ridge, a tab on one of said edges and a portion of said tab extending under 65 a side edge of an adjacent shingle when laid.

2. A shingle having side edges and end edges, 70 said end edges extending in a line approximately normal to the ridge of a roof upon which said shingle is so laid, and said side edges extending at acute angles to said ridge, a tab on one of 75 said edges and a portion of said tab extending under a side edge of an adjacent shingle when laid, said tab flaring in width toward its end.

3. A shingle having side edges and end edges, 75 said end edges extending in a line approximately

normal to the ridge of a roof upon which said shingle is so laid, and said side edges extending at acute angles to said ridge, a tab on one of said edges and a portion of said tab extending under a side edge of an adjacent shingle when 5 laid, and adapted to variably interlock with said side edge.

4. A shingle having side edges and end edges, 10 said end edges extending in a line approximately normal to the ridge of a roof upon which said shingle is so laid, and said side edges extending at acute angles to said ridge, a tab on one of said end edges and a portion of said tab extending under a side edge of an adjacent shingle when 15 laid.

5. A shingle having the general shape of a parallelogram, the lower edge of said shingle extending inwardly from the right hand side of the shingle to the left side thereof, there being a lug at one corner of said lower edge 20 adapted to interlock with the lower edge of a similar shingle.

6. A shingle having the general shape of a parallelogram, the lower edge of said shingle extending inwardly from the right hand side of the shingle to the left side thereof, there being a lug at one corner of said lower edge adapted to interlock with the lower edge of a similar shingle, the adjacent corner of said lower edge comprising an offset portion having one edge 25 extending approximately parallel with the upper edge of said shingle.

7. A shingle having the general shape of a parallelogram, the lower edge of said shingle extending inwardly from the right hand side of the shingle to the left side thereof, there being a lug at one corner of said lower edge adapted to interlock with the lower edge of a similar shingle, said lug being formed by a slot, said slot being co-extensive with one of the end edges 40 of said shingle.

8. A shingle having the general shape of a parallelogram, the lower edge of said shingle extending inwardly from the right hand side of the shingle to the left side thereof, there being a lug at one corner of said lower edge adapted to variably interlock with the lower edge of a similar shingle. 45

9. An assembly of shingles comprising shingles lapped in the same course, said shingles having 50 the general shape of a parallelogram and having a lower side edge extending at an acute angle to the ridge of a roof upon which said shingles are to be laid, said side edge of one of said shingles having a projecting portion of an adjacent shingle lapped thereunder at any predetermined point along its edge.

10. A surface covering comprising flexible shingles of generally rectangular form, each of said shingles having a locking tab of similar material to the shingle connected to a weather edge portion at one end thereof and projecting beyond said weather edge portion, each shingle being laid with the end edge thereof adjacent said tab laterally overlapping the opposite end edge of an adjacent shingle in the same course and with said tab engaged with the lower side edge of said adjacent shingle, with relative adjustment parallel to the course to vary the amount of lap between said adjacent shingles, and said shingles being adapted to be held against displacement by said locking tab and driven fastening means adjacent the edge interlock, said driven fastening means passing through one of 70 75 80 85 90 95

the shingles and covered by the adjacent shingle in lapping relation therewith.

11. A surface covering comprising flexible shingles of generally rectangular form, each of said shingles having a locking tab of similar material to the shingle lying substantially in the same plane as the shingle and extending from a lower portion of one end thereof, each shingle being laid with the end edge thereof adjacent 10 said tab, laterally overlapping the opposite end edge of an adjacent shingle in the same course and with said tab interlocked with the lower side edge of said adjacent shingle, with relative adjustment parallel to the course to vary the 15 amount of lap between shingles, said overlapped portion of said adjacent shingle being nailed adjacent said interlock and a portion of said interlocking tab underlying said adjacent shingle adjoining the lap and held from displacement by 20 the nailed overlapped portion of said adjacent shingle.

12. A surface covering comprising flexible shingles, each of said shingles having a shaped lower edge and a locking tab at one end thereof, each of said shingles being assembled with the tab end of one shingle laterally overlapping the opposite end of an adjacent shingle in the same course and having its tab interlocked with the shaped lower edge of said adjacent shingle, 30 said tab being positioned at the weather corner of the shingle, and the shaped lower edges of the shingles in a course extending obliquely to a line drawn through similar points on the weather corners of the shingles.

13. A shingle comprising a sheet of roofing material having top and bottom side edges, and end edges, there being a tab projecting from one of said end edges, said tab having an upwardly extending portion forming a notch with said end edge, and said tab being adapted to interlock at any point along a side edge of an adjacent shingle when laterally lapped therewith in a longitudinally extending course, said point of interlock being determined by the amount of lateral lap.

14. A flexible shingle having opposite end edges and opposite side edges, said opposite side edges extending generally parallel over their length, one of said end edges and the lower side edge constituting weather edges of the shingle, and 50 there being a locking tab extending from the weather edge portion at the weather end of the shingle, and said lower side edge adjacent said locking tab being set back for a portion of its length and adapted to receive the locking tab of an adjacent shingle when laid in a longitudinally extending course with the weather end of said adjacent shingle laterally lapped with 55 said first mentioned shingle.

15. A flexible shingle having end edges and side edges, a locking tab connected to an edge portion at a lower corner of the shingle, the tab corner portion of the lower side edge of the shingle being substantially straight, and a considerable 60 portion of the remainder being set back from

said substantially straight portion, the amount of said set-back measured substantially perpendicular to said tab corner edge portion being no greater than the extent of the tab measured in the same direction, and said shingle being adapted to be laid in longitudinally extending courses, with its end edge at the tab, laterally overlapping the opposite end edge of an adjacent shingle in the same course and with its locking tab engaged with the set-back edge portion of the adjacent shingle with adjustment of the overlap between said shingles.

16. A surface covering comprising shingles adapted to be laid in longitudinally extending courses, each shingle having a locking tab connected to an edge portion of the shingle and at a lower corner thereof, and the lower edge of said shingle adjacent the tab corner portion being set back for a considerable portion of its length, each shingle being laid with its end edge at the tab laterally overlapping the opposite end edge of an adjacent shingle in the same course and with its tab engaged with the set-back edge portion of said adjacent shingle, with relative adjustment parallel to the course to vary the amount of lap between said adjacent shingles, said lower edge portions of the shingle at the tab corners lying substantially on a straight line at the edge of the shingle course.

17. A shingle element of flexible material having end and side edges, the lower side edge of said shingle being stepped and comprising at least two substantially long parallel edges in the order of similar length connected by a short angular edge at their adjacent ends, and said shingle having a locking tab extending from an edge portion at one end of the shingle, said tab being adapted to engage one of the set-back edges of the lower edge of an adjacent shingle laterally lapped therewith in a longitudinally extending course, with relative adjustment along said edge to vary the amount of overlap between said adjacent shingles.

18. A shingle element of flexible material, said shingle having a locking tab extending from the lower edge portion of the shingle at one end thereof, and a second tab projecting from the lower shingle edge portion at the opposite end of the shingle, there being a recess extending between the tabs, and the lower edges of said tabs being substantially in line, a portion of said locking tab extending upwardly and adapted to interlock with the lower edge portion of an adjacent corresponding shingle in a course of shingles when laid in assembly.

19. A shingle having the general shape of an oblique angle parallelogram, the lower edge of said shingle having a projection adjacent one end and a locking tab projecting adjacent the other end, and said lower edge having a set-back portion between said tab and projection comprising a substantially straight edge joining the said tab and projection.

NORMAN P. HARSHBERGER. 65

CERTIFICATE OF CORRECTION.

June 29, 1937.

Patent No. 2,085,553.

NORMAN P. HARSHBERGER.

It is hereby certified that error appears in the printed specification of the above numbered patent requiring correction as follows: Page 2, second column, line 3, claim 3, for "acuate" read acute; and that the said Letters Patent should be read with this correction therein that the same may conform to the record of the case in the Patent Office.

Signed and sealed this 21st day of September, A. D. 1937.

Henry Van Arsdale
